UNITED STATES PATENT OFFICE.

ELLEN L. KELLEY, OF LITCHFIELD, CONNECTICUT.

BEDCLOTHES-FASTENER.

No. 914,287.

Specification of Letters Patent. Patented March 2, 1909.

Application filed May 8, 1908. Serial No. 681,626.

To all whom it may concern:

Be it known that I, ELLEN L. KELLEY, a citizen of the United States, residing at Litchfield, in the county of Litchfield and State of Connecticut, have invented certain new and useful Improvements in Bedclothes-Fasteners, of which the following is a specification, reference being had to the accompanying drawings.

10 My invention relates to improvements in bed clothes fasteners, and its object is to provide a simple and practical device of this character which may be readily applied to the foot piece or other part of the bed to effectively hold the bed clothes or covering thereon.

With the above and other objects in view, the invention consists of the novel features of construction and the combination and arrangement of parts hereinafter fully described and claimed, and illustrated in the accompanying drawings, in which—

Figure 1 is a plan view of a portion of a bed showing my improved bed clothes fastener applied thereto; Fig. 2 is a detail vertical section taken on the plane indicated by the line 2—2 in Fig. 1; and Figs. 3, 4, and 5 are enlarged detail plan, side, and end views of one end of the device.

30 My invention comprises a body member or bar 1 provided with a clamping device to engage the bed clothes and with clamps 2 or equivalent means for securing it to the bedstead. As illustrated, the clamps 2 are 35 adapted to engage the two corner posts of the foot piece of a metal bed, one being arranged at each end of the body 1, which latter is in the form of a flat bar or plate. Each of the clamps 2 has a body or hinge member 3 to 40 which are pivoted two clamping jaws 4 adapted to receive the bed post between them. The body portions of the jaws 4 are of semi-circular form and may be lined with felt or the like to prevent a brass or enamel 45 bed from being marred. The inner ends of the jaw members 4 are reduced and bent to form pivot eyes which are arranged between pivot eyes formed on the member or plate 3 by recessing its opposite edges and then 50 bending the remaining portions of said edges to provide pivot eyes. Pivot rods 5 pass through the aligned pivot eyes on the jaw members and the member or plate 3 and have their upper ends bent at right angles and 55 riveted or otherwise secured in the body bar 1 to support the latter. The free ends of the

jaw members 4 are bent angularly and apertured to receive a clamping bolt 6 provided with a winged nut 7.

The clamping device for attaching the bed clothes to the body bar 1 comprises a U-shaped frame 8 formed by a metal rod which has its body portion disposed parallel with and above the bar 1 and its depending ends 9 riveted or otherwise secured in said bar 1 adjacent to the ends of the latter. Slidably mounted on the ends 9 of the rod 8 is a clamping bar 10 which is adapted to clamp the bed clothes against said rod or frame 8. Said clamping bar is apertured to receive the ends 9 of the rod 8 and it is actuated by two or more screws 11 arranged in threaded openings in the body bar 1 and provided at their lower ends with finger pieces 12. The upper ends of said screws bear against the clamping bar 10 and, if desired, may be swiveled thereto.

The use of the invention will be readily seen upon reference to Figs. 1 and 2 in which the clamps 2 are shown applied to the corner posts of the foot piece and the bed clothes inserted between the bar 8 of the clamping frame and the slidably clamping bar 10. While this is the preferred manner of applying and using the invention it will be understood that the device may be otherwise arranged upon the bed. The device may be adapted to fit any bedstead and may be readily applied to, removed from and adjusted thereon. When used as illustrated, it will effectively hold the ends of the bed clothing.

While I have shown and described in detail the preferred embodiment of my invention I wish it understood that I do not limit myself to the precise construction set forth and that various changes in the form, proportion and minor details may be resorted to without departing from the spirit or sacrificing any of the advantages of the invention.

Having thus described my invention what I claim is:

1. A bed clothes fastener comprising a body bar, means thereon for securing bed clothes thereto, a bed post engaging clamp arranged at each end of said bar and comprising angular pivot rods each secured at one end to the body bar, a hinged plate or member between said pivot rods, swinging jaw members attached to the hinged member or plate by said pivot rods and a clamping screw for uniting said jaw members.
2. A bed clothes fastener comprising a

- 23
- body bar, a rod of U-form having its parallel ends secured to said bar, said rod forming a bed clothes engaging frame, a clamping bar slidable upon the ends of said rod, screws arranged in said body bar and adapted to actuate the clamping bar to clamp the clothes against said rod, and hinged bed posts engaging clamps secured to the body bar adjacent its ends.
- 10 3. A bed clothes fastener comprising a body bar, a rod of U-form having its parallel ends secured adjacent to the ends of said body bar, said rod forming a bed clothes engaging frame, a clamping bar slidable upon the ends of said rod and adapted to clamp bed clothes between it and the central portion of said rod, two screws arranged in threaded openings formed in the body bar adjacent to its ends, said screws being adapted to actuate the clamping bar, and hinged bed post engaging clamps, each clamp being provided with two offset attaching rods fixed to the body bar adjacent to its ends.
- 15
- 20
4. A bed clothes fastener comprising a straight body bar having threaded openings adjacent its ends, a rod of U-form having its parallel depending ends secured to the top of the body bar, said rod forming a bed clothes engaging frame, a flat clamping bar apertured at its ends to slidably receive the ends of said rod and adapted to clamp the bed clothes between it and the central portion of said rod, two screws arranged in the threaded openings in the body and having their upper ends bearing against the bottom of the clamping bar and their lower ends formed with finger pieces, bed post engaging clamps and offset attaching rods between said clamps and said body bar.

In testimony whereof I hereunto affix my signature in the presence of two witnesses.

ELLEN L. KEMLEY.
